UNITED STATES PATENT OFFICE.

WILLIAM H. HAWKEN, OF HONESDALE, PENNSYLVANIA, ASSIGNOR TO IRVING CUT
GLASS COMPANY, OF HONESDALE, PENNSYLVANIA.

DESIGN FOR A GLASSWARE VESSEL.

44,003.

Specification for Design.

Patented May 13, 1913.

Application filed March 29, 1913. Serial No. 757,707. Term of patent 7 years.

To all whom it may concern:

Be it known that I, WILLIAM H. HAWKEN, a citizen of the United States, residing at Honesdale, in the county of Wayne and State of Pennsylvania, have invented a new, original, and ornamental Design for Glassware Vessels, of which the following is a specification, reference being had to the accompanying drawing, forming part thereof.

The figure is a side view of a glassware vessel.

I claim:—

The ornamental design for a glassware vessel, as shown.

WILLIAM H. HAWKEN.

Witnesses:

R. L. REICHENBACHER,
WILLIAM SEITZ.
